UNITED STATES PATENT OFFICE.

CHARLES STIRIZ, OF NEW YORK, N. Y.

RESPIRATOR.

1,071,109.

Specification of Letters Patent. Patented Aug. 26, 1913.

Application filed March 2, 1909. Serial No. 480,503.

To all whom it may concern:

Be it known that I, CHARLES STIRIZ, a citizen of the United States, residing at the borough of Manhattan, in the city, county, and State of New York, have invented certain new and useful Improvements in Respirators, of which the following is a specification, reference being had therein to the accompanying drawings, which form a part thereof.

My invention relates to respirators and more particularly to that class thereof adapted for curative uses.

The main object of the invention is to provide a respirator, the construction and mode of operation of which will be such as to insure the clarification of the air drawn into the lungs of a patient, for the treatment of tuberculosis and other pulmonary ailments.

20 A further object is to provide a device of this character utilizing an electric spark for the purposes above specified, the closing of the circuits to the spark gap being automatically controlled by the inhalation and exhalation of the breath of the wearer.

A still further object is to provide a device of this character wherein the intensity of the spark may be so regulated as to adapt the device to different users, or to a temporary condition of the user which may necessitate a gradual increase in the strength of the spark.

A still further object is to provide in a device of this character, means whereby the nature of the spark gaps may be increased if desired, either with or without an increase in the length of the spark.

A still further object is to provide a device employing a valve construction whereby the circuit to the spark gap may be automatically opened and closed by the exhalation and inhalation of the user, and the movements of said valve will increase the opening as the circuit to the spark gap is opened, and will diminish said opening as the user inhales the air through the apparatus, thus not only giving a breathing exercise, but bringing the air in small volume within the range of the spark.

50 A still further object is to provide a device of this character which will be so wired and assembled as to permit its use without likelihood of electric shock to the user. And a still further object is to provide a device of this character which may be inexpensively produced and simple in design, so as to be

capable of general use, as distinguished from use by medical experts.

The invention consists primarily in the novel features of construction and combination of parts hereinafter set forth and described, and more particularly pointed out in the claims hereto appended.

Referring to the drawings:—Figure 1 is a longitudinal section through a respirator embodying my invention in its broader form, and Fig. 2 is a section on the line 2—2 of Fig. 1, and also embodying therein a diagrammatic showing of the circuits, and the means arranged therein for controlling the intensity and the volume of the spark within the respirator.

Like letters refer to like parts throughout the several views.

In the embodiment of my invention shown in the drawings, I have shown at *a* a cylindrical casing one end of which is so shaped as to be adapted to fit about the mouth and nostrils of a person and the other end of which opens outwardly. Any suitable means, as the head strap *b*, may be used to hold the appliance in the position shown. The casing *a* is preferably made of an insulating material such as vulcanite, fiber, or papier maché, in order to prevent the user receiving a shock through said casing. Mounted adjacent to the open end of the casing *a* is an oscillating valve flap *c*, which flap is overbalanced so as to normally close through gravity. The flap *c* is mounted in the casing *a* by means of pivots secured to said flap and passing through suitable bearings formed in the said casing. The valve flap *c* has a plurality of perforations therein and said flap carries one terminal *d* of an electrical circuit presented inwardly thereof, relative to the casing *a*. This terminal may take any desired form, but preferably I employ a disk in order to permit the number of opposed terminals to be multiplied as desired.

95 with a resultant distribution of the electric sparks across the duct adjacent to said flap valve. In the accompanying drawings, I have shown three such terminals *e*, *f*, and *g*, adjustably mounted in the insulating casing *a* which terminals extend to a point adjacent to the periphery of the said disk *d*. The outer end of each said terminal *e*, *f*, *g* is provided with a binding post, to facilitate the attachment of the terminal wires *e'*, *f'* and *g'* thereto. Said terminals *e*, *f* and *g* are preferably made adjustable by screw

threads, on the outer ends thereof, such adjustment being for the purpose of varying the width of the gap and consequently the length of the spark. The outer ends of the 5 pivot d' , by means of which the flap c is pivotally mounted relative to the casing a , carry respectively a binding post by means of which the terminal wire d^2 may be attached to said pivot.

10 In the accompanying drawings I have shown the use of the invention in connection with a dynamo circuit, the dynamo being indicated at h , and being shown to be in communication with the pivot d' through the 15 wire d^2 . The other terminal wire h' of the dynamo is in communication with the terminals e, f, g , respectively, my invention contemplating the arrangement in the circuit of suitable appliances as a rheostat i , and 20 the switches j, j' and j^2 whereby the intensity of the spark may be controlled or the number of sparks varied at will. One terminal of each switch j, j' and j^2 is wired in any approved manner to one terminal of the 25 rheostat, and the other terminals of said switches are in electric connection with the wires e', f' and g' . It will be observed that by this arrangement the circuit to any terminal e, f or g may be opened, thus permitting 30 the use of any of these terminals for the development or formation of a spark within the casing a and adjacent to the flap c .

The operation of my herein described respirator is substantially as follows. The 35 mouth and nostrils of the user having been inserted in one end of the casing a and the casing held by straps b in a manner to prevent the escape or entrance of air through that end, the rheostat switch i , is set 40 upon any of the contacts in order to increase or reduce the resistance and vary the intensity of the current passing to the terminals e, f, g . One or more of the switches j, j' and j^2 may then be set to close the circuits 45 to any or to all of the terminals e, f, g at which time the spark will be formed between said terminals and the disk d , the circuit being completed through said disk, the pivot d' thereof, and the terminal d^2 . As the user exhales his breath, 50 the air currents will raise the lower portion of the flap c thus increasing the gap between the disk d and the terminals e, f, g to a point where the current will not jump 55 same. This opening of the flap will at the same time increase the size of the discharge opening through the open end of the casing a and rapidly clear said casing of the foul air. When the user inhales or draws in his 60 breath, gravity supplemented by the suction induced by breathing, will draw the flap c into its former position, reducing the gap and forming a spark or sparks directly in the path of the inflowing air, the effect 65 of this spark being not only to clarify

the air, but to heat same slightly in a manner to prove beneficial to the lungs, nostrils or throat of the user. The reduced size of the openings through which the air must pass will tend to retard the flow of the air being drawn into the lungs, thus insuring its thorough intimate contact with the said sparks and at the same time causing a muscular exertion which will be beneficial to the 70 user.

If desired, any well known electrical appliances as a Ruhmkorff coil, may be included in the electrical circuit together with a circuit interrupter for the purpose of increasing the intensity of the current and the resulting spark, and permitting the use 75 of the appliance with a battery.

It is not my intention to limit the invention to the precise details of construction shown in the drawings, it being apparent 80 that such may be modified without departing from the spirit and scope of the invention.

Having described the invention, what I 85 claim as new, and desire to have protected by Letters Patent, is:—

1. In a respirator, an air duct having an inlet opening therein, an electric circuit including therein oppositely disposed terminals within said duct and spaced apart to form an air gap adjacent to said inlet opening whereby the air passing through said opening is subjected to an electric spark across said gap, and means actuated by the passage of air through said duct for automatically increasing and diminishing the width of said gap to interrupt the sparking. 95

2. In a respirator, an air duct having an inlet opening therein, a movable valve member controlling said opening, an electric circuit included therein oppositely disposed terminals carried by said duct and said valve member respectively, said terminals being spaced apart to form an air gap, whereby the air passing through said opening is subjected to an electric spark across said gap, and a pivotal support for said valve member whereby the air passing through said duct automatically actuates said valve member to produce or prevent 100 the sparking at said gap. 105

3. In a respirator, an air duct having an inlet opening therein, a valve controlling said opening, a terminal carried by said valve member, a terminal adjustably mounted in said duct whereby a gap is formed between said terminals, and the length of said gap may be varied, an electric circuit including said terminals therein. 110 115

4. In a respirator, an air duct having an inlet opening therein, a valve controlling said opening, a terminal carried thereby, a plurality of terminals carried by said duct, said last mentioned terminals being spaced away from said valve terminal, and all said 120 125

- 5 terminals being included in an electric circuit, and means included in said circuit whereby the circuit to any of said last mentioned terminals may be opened to vary the length of the spark within said conduit.
- 10 5. In a respirator, an air duct having an inlet opening therein, a valve controlling said opening, a terminal carried thereby, a plurality of terminals carried by said duct, said last mentioned terminals being spaced away from said valve terminal, and all said terminals being included in an electric circuit and means included in said circuit whereby the circuit to any of said last mentioned terminals may be opened to vary the volume of the spark within said conduit, and means also included in said circuit for varying the intensity of the current passing through said last mentioned means.
- 15 20 6. In a respirator, an air duct having an

inlet opening therein, a flap valve mounted in said duct at a point above the center thereof whereby gravity will tend to close said valve, said valve having a plurality of openings therethrough whereby the closing of the valve will result in a reduction in the volume of air passing therethrough, a terminal carried by said valve and an oppositely disposed terminal carried by said duct, said terminals being spaced apart when the valve is closed to leave a spark gap, and an electric circuit including therein both said terminals. 25 30

In witness whereof, I have hereunto affixed my signature this 20th day of February, 1909, in the presence of two witnesses.

CHARLES STIRIZ.
